UNITED STATES PATENT OFFICE.

FRANK L. MACKEMER, OF PEORIA, AND ELI M. MACKEMER, OF GALESBURG, ILLINOIS.

DESIGN FOR AN AUTOMOBILE-BODY.

50,448.

Specification for Design.

Patented Mar. 13, 1917.

Application filed January 19, 1917. Serial No. 143,387. Term of patent 3½ years.

To all whom it may concern:

Be it known that we, FRANK L. MACKEMER and ELI M. MACKEMER, citizens of the United States, and residents, respectively, of Peoria, Peoria county, Illinois, and Galesburg, Knox county, Illinois, have jointly invented a new, original, and ornamental Design for Automobile-Bodies, of which the following is a specification, reference being had to the accompanying drawing, forming part thereof.

In the accompanying drawing, Figure 1 is a side elevation, and Fig. 2 a top plan, together showing our new design.

We claim:

The ornamental design for an automobile body, as shown.

FRANK L. MACKEMER.
ELI M. MACKEMER.
